[57] CLAIM

The new ornamental design for a lipstick or similar article, as shown.

DESCRIPTION

FIG. 1 is a top plan view of a lipstick or similar article showing our new design.

FIG. 2 is a rear elevational view thereof;

FIG. 3 is a side elevational view thereof, the side opposite being a mirror image of the side shown;

FIG. 4 is a front elevational view thereof; and

FIG. 5 is a bottom plan thereof.

FIG. 1.

FIG. 2.

FIG. 3.

FIG. 4.

FIG. 5.
